UNITED STATES PATENT OFFICE.

CARL JOHAN HULT, OF STOCKHOLM, SWEDEN, ASSIGNOR TO AKTIEBOLAGET SVENSKA PRESSGJUTERIET, OF STOCKHOLM, SWEDEN, A CORPORATION.

APPARATUS FOR PRESS CASTING.

Application filed April 22, 1922. Serial No. 556,082.

To all whom it may concern:

Be it known that I, CARL JOHAN HULT, manufacturer, a subject of the King of Sweden, residing at 44 Rorstrandsgatan, 5 Stockholm, Sweden, have invented certain new and useful Improvements in Apparatus for Press Casting, of which the following is a specification.

The present invention relates to an arrangement in press casting apparatus, and the object of the invention is to provide an apparatus wherein the closing of the mould as well as the retaining thereof during the casting process, and the opening thereof 15 after the casting process has been completed, may be easily effected by a single man. In the apparatus as heretofore known, this work generally requires at least two men, by reason of the device employed for the 20 work being unmanageable and otherwise unsuitable.

The invention is principally characterized by this that the members, by means of which the mould is retained during the casting process, are displaceable to and fro on fixed guides in such a manner that the member situated adjacent to the casting nozzle of the apparatus may be moved outwardly from the nozzle by the action of 25 springs, whereas the other member is connected with a device by means of which it may be displaced to and fro on the guides.

The accompanying drawing illustrates an embodiment of the invention. Fig. 1 shows the apparatus in elevation, the members holding the mould being illustrated in section, and Fig. 2 shows the apparatus in plan view.

1 is the furnace pertaining to the apparatus, within which are disposed the melting crucible and the parts serving to press out the molten metal. Attached to the side of the furnace 1 are guides 2 supported at their outer ends by posts 3. On the guides, 40 the plates or frames 4 and 5 are mounted so that they may be displaced, and between said plates or frames the mould, that is to say the mould halves, are disposed and adapted to be jammed together, while the 45 two plates and the intermediate mould are adapted to be moved unto the furnace 1, so that the sleeve 6 provided in the plate 4 will be brought tight up against the outlet 7 of the furnace. According to Fig. 2 the 50 plate or frame 4 is rigidly connected with

rods 8 which are displaceable to and fro in guides 9 arranged in the furnace, whereas between the guides 9 and the plate 4, springs 10 are arranged on the rods 8. Screwed onto the outer threaded ends of the rods 8 are nuts 11, adjustable on the rods, and forming abutments co-operating with the guides 9 to limit the displacement of the rods 8 outwards to the right according to the drawing. This displacement is effected 65 through the action of the springs 10. Connected with the plate or frame 5 is the cross piece 12, the ends of which are threaded on screws 13 attached to the plate 5, said screws 13 being tube-shaped and, in turn, threaded 70 on the guides 2. The cross piece 12 is adjustable on the screws 13 by means of nuts 14 and 15, so that the cross piece may be adjusted, as desired, to a distance from the plate 4 corresponding to the width of the 75 mould being used for the moment. The cross piece 12 is connected by means of links 16 with toothed segments 17. Meshing with these segments are pinions 18 on shaft 19 which may be rotated by means of the 80 levers 20.

In the position of the parts according to the drawing, the mould is assumed to be jammed between the plates or frames 4, 5, while plate 4 is pressed unto the outlet 7 85 of the furnace so that the metal can be pressed into the mould. When, on the casting process having been completed, the mould is to be removed from the furnace and taken apart, shaft 19 is turned to the 90 left (Fig. 1), the pinions 18 then actuating the segments 17 so that the latter will draw the plate 5 outwardly on the guides 2 by means of the links 16. Then the mould and also the plate 4 will follow by being displaced outwards through the action of the 95 springs 10. This displacement continues until the nuts 11 abut against the guides 9, when the plate 4 is caused to stop. The outwards-movement of the plate 5 is continued, said plate being thus moved from the plate 4, so that the mould halves are separated and the casting may be removed. By again turning the shaft 19 to the right, 100 the parts are actuated in the reversed sequence, so that the plates 4 and 5 are again brought closer together so as to jam the mould between them, whereupon the plates are again moved toward the furnace, together with the mould, so that the sleeve 6 110

of the plate is pressed against the nozzle 7. To regulate the extent of movement between the pinions 17 and the links 16, there are provided set screws 21 in the former ones, adapted to be screwed against the link rods 16.

What I claim as new and desire to secure by Letters Patent of the United States is:—

1. In a die-casting apparatus, fixed guides, mould holding members reciprocably mounted on said guides, a casting nozzle arranged adjacent one of the holding members, rods carried by the last mentioned holding member, guides for said rods, springs arranged between the second mentioned guides and said mould holding member normally tending to move the latter away from the casting nozzle, means for limiting the displacement of said rods and the holding member carried thereby, and means for reciprocating the other holding member along the first mentioned guides.

2. A die-casting apparatus as claimed in claim 1 characterized in that the said recip-

rocating means for said other holding member includes a cross rod connected with the second mentioned holding member, rotatable pinions, toothed segments meshing with said pinions, and links connecting the toothed segments with the cross piece whereby upon rotation of the pinion the toothed segments are actuated and the holding member is moved outwardly.

3. A die-casting apparatus as claimed in claim 1 characterized in that the reciprocating means for the second mentioned holding member includes a cross piece, means for reciprocating said cross piece, screws carried by the holding member and adjustable in the cross piece whereby the extent of movement of the holding member may be varied according to the size of the mould.

In testimony whereof I affix my signature in presence of two witnesses.

CARL JOHAN HULT.
